UNITED STATES PATENT OFFICE.

ALEXANDER TEMPLETON, OF PATERSON, NEW JERSEY.

SHUTTLE-TENSION DEVICE.

Application filed January 24, 1927. Serial No. 162,944.

The tension device employed most commonly in shuttles for broad silk looms comprises a line of fixed pins, a lever having thread eyelets alternating with the pins, and a rubber band normally tending to hold the lever so that the thread, passing in alternate engagement with the eyelets and pins, extends zig-zag fashion in the shuttle. The pins, the bearing for the lever, a mortise or slot for the latter in one side of the shuttle and other incidents of this type of tension device greatly weaken the body of the shuttle; the elastic band deteriorates and breaks, requiring frequent replacement; and defects exist in the actual tension, such as that caused by the lever becoming loose by wear of its bearing, by variations in the resistance of different elastic bands, etc. The object of this invention is to provide a loom shuttle, and especially a broad loom shuttle, with a tension means which shall avoid these faults. In accomplishment of this purpose I eliminate the lever and I also eliminate the rubber band, among other things substituting for the latter a spiral spring which I operatively arrange in the shuttle in the novel manner hereinafter set forth.

In the drawing, Fig. 1 is a plan of a shuttle embodying my tension means;

Fig. 2 is a similar view, showing the tension spring extended;

Fig. 3 is a side elevation; and

Figs. 4 and 5 are sectional views on lines 4-4 and 5-5 of Figs. 1 and 3, respectively. 1 is the shuttle body and 2 a filling or weft thread package of the endwise-delivery type suitably supported in the cavity 3 there-in, as on a spindle 2^a, said cavity having a filling outlet 3^a at one side thereof. Instead of this cavity being partitioned off from the cavity provided for the tension means as is usual, it is in the present case extended forward, as shown, so to accommodate both the weft package and the tension means and is without cover or overhang over the latter, thereby rendering the tension means readily accessible; but these details are not indispensable.

In the forward end of the cavity 3 is arranged an angle-plate 4 (which may be regarded as a removable though stationary part of the body 1) having one wall vertical and projecting upwardly and bearing against the end surface of the cavity and the other

wall horizontal and projecting rearwardly and resting on the floor of the cavity, being held in place by a screw 5. The vertical wall has two apertures or holes 6, one above the other and both arranged approximately in a vertical plane coincident with the longitudinal axis of the shuttle.

Upstanding from the horizontal wall of the angle-plate are two thread-guides 7, each being here a hook whose rebent or hook-portion 7^a is turned forward; they may have threaded shanks screwed into suitable holes tapped into said wall of the angle-plate so that when and if they become worn by the filling they may be readily removed and replaced with new ones. They are arranged preferably on opposite sides of the aforementioned plane, suitably spaced from each other.

The filling or thread A, reaching forward from the package 2, bridges the shanks of the guides 7 and then extends from the shuttle through the filling outlet 3^a. But between the guides it also extends through an eye ring 8 forming a movable thread-guide, which ring may be formed of glass. This ring travels on the lower one of the forwardly extending approximately straight legs 9^a, 9^b of a wire guide 9 here consisting of a piece of wire bent to form the two legs and at its crotch having a loop or eye 9^c; this guide is held in place by having the ends of its legs inserted in the holes 6 of the angle-plate and by a headed screw or the like 10 passed through its loop 9^c and driven into the side of the shuttle body from the cavity 3. The ring or thread-guide 8 is subject to the pull of a light spiral spring 11 which is coiled about the upper leg 9^a of the guide 9, having one end attached to the screw 9^c and the other to the thread guide. The parts 8-11 may be regarded as elastic means engaged with the bridging part of the thread (between 7-7) and connecting the same and the shuttle body and having sliding engagement with the guide 9 and normally holding said part of the thread in the form of a loop, as shown in Fig. 1.

The operation of the improved tension means will be apparent to those skilled in the art. The shuttle is easily threaded either by shifting the thread-guide into position between the guides 7 and then with a weft-hook drawing the filling through the thread-guide 8 and so as to extend in the stated bridging relation to said guides 7, or

by drawing it through guide 8 and then engaging it from above with the (hook-shaped) guides 7. If the thread-guide has an eye or opening of ample size with respect to the wire-leg 9^b of the guide 9 on which it is mounted, or substantially as shown, it will travel at all times with perfect freedom. It is further entirely free to turn on such leg of the guide, thus reducing the possibility of the filling forming nicks therein to catch and break the filling. Repairs or replacement of the guide 9, thread-guide 8 or spring are always readily possible because removal of the guide requires removal of only a single securing element—the device 10; indeed, replacement of the thread-guide 8 is possible by simply withdrawing the free ends of guide 9 from the holes 6, it having for this purpose a certain degree of flexibility.

20 Having thus fully described my invention what I claim and desire to secure by Letters Patent is:

1. A loom shuttle including, with a shuttle body and means to support therein an endwise-delivering weft-thread package with its longitudinal axis lengthwise of the shuttle, spaced thread-guides to be bridged by the thread arranged in endwise spaced relation to said package and in a line transverse of said axis, and a movable thread-guide engaged by the part of the thread bridging the spaced thread-guides and spring-urged from the latter lengthwise of said axis and movable toward them under the pull of the thread.

2. A loom shuttle including, with a shuttle body and means to support therein an endwise-delivering weft-thread package with its longitudinal axis lengthwise of the shuttle, spaced thread-guiding hooks to be bridged by the thread arranged in endwise spaced relation to said package and in a line transverse of said axis, and a movable thread-guide engaged by the part of the thread bridging said hooks and spring-urged from the latter lengthwise of said axis and movable toward them under the pull of the thread.

3. A loom shuttle including, with a shuttle body, spaced thread-guides to be bridged by the weft-thread, an elongated guide extending substantially toward said thread guides and held in the shuttle body, and

a movable thread-guide slidable on and lengthwise of said elongated guide and engaged by the part of the thread bridging said thread-guides and spring-urged from the latter and movable toward them under the pull of the thread.

4. A loom shuttle including, with a shuttle body, spaced thread-guides to be bridged by the weft-thread, an elongated guide extending substantially toward said thread guides and held in the shuttle body, a movable thread-guide movable lengthwise of said elongated guide and engaged by the part of the thread bridging the first-named thread-guides, and a spring coiled on said elongated guide and having one end fixed and the other attached to said movable thread-guide and normally holding the same retracted from the first-named thread-guides.

5. A loom shuttle including, with a shuttle body, spaced thread-guides to be bridged by the weft-thread, an elongated guide extending substantially toward said thread guides and held in the shuttle body, and elastic means engaged with the part of the thread between said thread-guides and connecting the same and said body and having sliding engagement with said elongated guide and normally holding said part of the thread in the form of a loop.

6. A loom shuttle including, with a shuttle body, spaced thread-guides to be bridged by the weft-thread, an elongated guide having two substantially parallel legs extending substantially toward said thread-guides and held in the shuttle body, a movable thread-guide slidable on one leg and a spring coiled on the other leg and connecting said movable thread-guide with said body.

7. A loom shuttle including, a shuttle body formed with a cavity and an aperture opening into the same, a flexible elongated guide having an end thereof removably entered into the aperture of the body and being attached to said body remote from said aperture, spaced thread guides in said body, and a thread-guiding device slidable on said elongated guide and spring-urged from said thread guides.

In testimony whereof I affix my signature.

ALEXANDER TEMPLETON.
